UNITED STATES PATENT OFFICE.

SOLOMON G. SALOMON, OF FAR ROCKAWAY, NEW YORK.

DESIGN FOR A PACKAGE OF CIGARS.

4C,968.

Specification for Design.

Patented Feb. 16, 1915.

Application filed November 7, 1914. Serial No. 870,911. Term of patent 3½ years.

To all whom it may concern:

Be it known that I, SOLOMON G. SALOMON, a citizen of the United States, residing at No. 6 Oak street, Far Rockaway, in the borough and county of Queens and State of New York, have invented a new, original, and ornamental Design for a Package of Cigars, of which the following is a specification, reference being had to the accompanying drawing, forming part thereof.

Figure 1 is a perspective view of a package of cigars, showing my new design. Fig.

2 shows one of the two like ends of the cigar band.

The reverse side of the package is the same as the front except for the overlapping ends of the band.

I claim:

The ornamental design for a package of cigars as shown.

SOLOMON G. SALOMON.
